(57) **CLAIM**

The ornamental design for a dual chamber food jar, as shown and described.

DESCRIPTION

FIG. 1 is a perspective view of the dual chamber food jar;
FIG. 2 is a right side view of the dual chamber food jar;
FIG. 3 is a left side view of the dual chamber food jar;
FIG. 4 is a front view of the dual chamber food jar;
FIG. 5 is a rear view of the dual chamber food jar;
FIG. 6 is a top view of the dual chamber food jar;
FIG. 7 is a bottom view of the dual chamber food jar;
FIG. 8 is a front view of the dual chamber food jar in a partially opened position;
FIG. 9 is a perspective view of the dual chamber food jar in an opened position;
FIG. 10 is a right side view of the dual chamber food jar in the opened position;
FIG. 11 is a left side view of the dual chamber food jar in the opened position;
FIG. 12 is a front view of the dual chamber food jar in the opened position;
FIG. 13 is a rear view of the dual chamber food jar in the opened position;
FIG. 14 is a top view of the dual chamber food jar in the opened position;
FIG. 15 is a bottom view of the dual chamber food jar in the opened position;
FIG. 16 is a perspective view of a second embodiment of a dual chamber food jar;
FIG. 17 is a right side view of the second embodiment of the dual chamber food jar;
FIG. 18 is a left side view of the second embodiment of the dual chamber food jar;
FIG. 19 is a front view of the second embodiment of the dual chamber food jar;
FIG. 20 is a rear view of the second embodiment of the dual chamber food jar;
FIG. 21 is a top view of the second embodiment of the dual chamber food jar; and
FIG. 22 is a bottom view of the second embodiment of the dual chamber food jar.
The broken lines showing in the figures are included for the purpose of illustrating portions of the dual chamber food jar that form no part of the claimed design.
